UNITED STATES PATENT OFFICE.

GUNTHER PHILIP WILD, OF PHILADELPHIA, PENNSYLVANIA.

DOOR FASTENER.

Application filed April 9, 1925. Serial No. 21,780.

This invention relates, generally stated, to door fasteners and has more especial relation to latch mechanism for refrigerator doors, cold storage room doors and the like.

5 The leading object of the present invention is to provide a door fastener of the character stated in which is combined simplicity and efficiency of structure, simplicity in manipulation, quick and positive locking operation and cheapness of manufacture. Other objects reside in the provision of general details of construction and arrangement and combination of parts for attaining the results sought by said leasing object.

10 15 Other and further objects not at this time more particularly pointed out will be hereinafter referred to.

The invention consists of the novel construction hereinafter described and finally 20 claimed.

The nature, characteristic features and scope of the invention will be more fully understood from the following description taken in connection with the accompanying 25 drawings forming part hereof, and in which:

Fig. 1 is a view in front elevation, of latch mechanism embodying the invention.

Fig. 2 is a view in section taken upon the 30 line 2—2 of Fig. 1.

Fig. 3 is a view in end elevation of the keeper parts shown in Figs. 1 and 2.

Fig. 4 is a view in section taken upon the 35 line 4—4 of Fig. 1.

Fig. 5 is a view in elevation of the keeper detached, and

Fig. 6 is a fragmentary view illustrating details of construction of the end of the latch operating lever shown in Fig. 2.

40 For the purpose of illustrating my invention I have shown in the accompanying drawings several forms thereof which are at present preferred by me, since the same have been found in practice to give satisfactory 45 and reliable results, although it is to be understood that the various instrumentalities of which my invention consists can be variously arranged and organized and that my invention is not limited to the precise arrangement and organization of the instrumentalities as herein shown and described.

In the drawings, the reference numeral 1, designates a door-jamb and reference numeral 2 designates a door hinged with respect hereto. A description will be given 50 first of the keeper parts as carried by the

door-jamb and thereafter a description of the latching elements as carried by the door will be given. Fixed to the door-jamb 1, as by the screws 3 is a casting 4, best seen in Figs. 1, 2 and 3. This casting has a longitudinal bore 5 fitted within which is a keeper 6 the rear of which is apertured as at 7, fitted within which is a coiled spring 8 abutting against the rear wall of casting 4 and normally pressing said keeper 6 toward the right in Figs. 1 and 2. The nose of the keeper is flat as at 9 and the opposite faces are inclined as at 10 and 11. The nose of the keeper is also provided with shoulders 12 and 13 which are arranged to abut against a plate 14, screwed as at 15, see Fig. 3, to the front of casting 4 to limit the forward movement of said keeper.

Taking up now the latching mechanism 75 as carried by door 2 and which cooperates with the keeper just described, reference numeral 16 designates an elongated plate secured to the door 2 as by screws 17. This plate is substantially T-shaped, as seen in Fig. 1; is perforated at one end as at 18; and carried at its other end a fixed detent 19 in the form of a plate of hardened metal. Having hinged relation with the plate 16 is a movable detent 20. Such detent is best seen in Fig. 4. The plate 16 is provided with lugs 21, pivotally carried by which is a rod 22, fixed upon which by means of a pin 23 is said detent 20, the bevelled nose 24 of which is aligned with detent 19, see Fig. 2. A coiled spring 25 is interposed between plate 16 and the nose end of detent 20 to normally maintain the stop 26 of the opposite end of said detent 20 in abutting relation with plate 16, see Fig. 2. The stop 26 and the adjacent part of the detent form a hand grip portion 27 so that to open the door the operator grasps part 27 and pulls outwardly thus moving the bevelled end 24 of the detent inwardly to ride over and push inwardly keeper 11. As keeper 11 moves to the left in Fig. 2, and as the operator still pulls upon door 2, the fixed detent 19 rides outwardly over the receding end of the keeper and thus frees the door for ready opening. It is thus seen that normally the keeper is between both fixed and movable detents, and abuts against the fixed detent, there being however clearance between the movable detent and said keeper as clearly seen in Fig. 2. Obviously to close the door 1, the fixed detent first moves the keeper in-

105 110

wardly to permit the fixed detent to pass beyond said keeper. When the door 1 is in locked position as seen in Fig. 2, the said door may be opened from within a refrigerating room or the like by pushing upon 5 knob 26 of rod 29 and thus moving end 30 of said rod 29 against the end 28 of detent 27 the detent is moved about its pivotal point 22 to push inwardly the spring pressed 10 plunger 11 and thus permit detent 19 to pass outwardly beyond the spring pressed keeper 11. The end 30 of rod 29 is provided with a hardened steel ball 31 which rests within the concaved part 32 of the end 28 of detent 15 27 and forms a good bearing and thus doing away with pivotal or other connections. A pin 33 is employed to limit the rearward movement of rod 29.

It will now be apparent that I have devised a novel and useful construction which embodies the features of advantage enumerated as desirable in the statement of the invention and the above description and while I have in the present instance shown 20 25 and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

35 1. A latch device of the character stated comprising a keeper having opposed bevelled edges, said keeper being mounted upon the jamb of a door and having a spiral spring arranged within said keeper, a plate 40 having a fixed detent carried by a door and normally adapted to abut against the inner bevelled face of said keeper, a spring pressed detent mounted upon a vertical axis of said 45 plate and adapted to swing in a horizontal manner and normally abutting against the opposite face of said keeper whereby outward movement of said detent will move said keeper inwardly to permit release of the fixed plate and means penetrating 50 said door and engaging said spring pressed detent for manual release thereof.

55 2. A latch device of the character stated comprising a keeper mounted for horizontal movement and having opposed bevelled edges, said keeper having a spiral spring arranged therein, said keeper being mounted upon the jamb of a door, a plate having a fixed detent carried by a door and normally adapted to abut against the inner bevelled 60 face of said keeper, a spring pressed detent mounted upon a vertical axis of said plate and adapted to swing in a horizontal manner and normally abutting against the oppo-

site face of said keeper whereby outward movement of said detent will move said keeper inwardly to permit release of the fixed plate and means penetrating said door and engaging said spring pressed detent for manual release thereof.

3. A latch device of the character stated 70 comprising a keeper having opposed bevelled edges, said keeper having a spiral spring arranged therein, said keeper being mounted upon the jamb of a door, a plate having a fixed detent carried by a door and normally adapted to abut against the inner bevelled face of said keeper, a spring pressed detent arranged to form a hand grip mounted upon a vertical axis of said plate and adapted to swing in a horizontal manner and normally abutting against the opposite face of said keeper whereby outward movement of said detent will move said keeper inwardly to permit release of the fixed plate and means penetrating said door and engaging said spring pressed detent for manual release 75 80 85 thereof.

4. A latch device of the character stated comprising a spring pressed keeper having opposed bevelled edges, said keeper being mounted upon the jamb of a door, a plate having a fixed detent carried by a door and normally adapted to abut against the inner bevelled face of said keeper, a spring pressed detent mounted upon a vertical axis of said plate and adapted to swing in a horizontal manner and normally abutting against the opposite face of said keeper whereby outward movement of said detent will move said keeper inwardly to permit release of the fixed plate, and a rod passing through 100 said door for abutting against the free end of said detent said rod being provided with a hardened steel ball.

5. A latch device of the character stated comprising a keeper having a flat vertical nose with a bevelled portion upon opposite sides thereof, said keeper having a spiral spring arranged therein, said keeper being mounted upon the jamb of a door, a plate having a fixed detent carried by a door and normally adapted to abut against the inner bevelled face of said keeper, a spring pressed detent mounted upon a vertical axis of said plate and adapted to swing in a horizontal manner and normally abutting against the opposite face of said keeper whereby outward movement of said detent will move said keeper inwardly to permit release of the fixed plate and means penetrating said door and engaging said spring pressed detent for 110 115 120 manual release thereof.

In testimony whereof, I have hereunto signed my name.

GUNTHER PHILIP WILD.
